UNITED STATES PATENT OFFICE

106,323

DESIGN FOR A ROLLER SKATE

Norman W. Norman, Chicago, Ill., assignor to Edward A. Grange, Chicago, Ill.

Application May 7, 1937, Serial No. 69,223

Term of patent 14 years

To all whom it may concern:

Be it known that I, Norman W. Norman, a citizen of the United States, residing at Chicago, in the county of Cook and State of Illinois, have invented a new, original, and ornamental Design for a Roller Skate, of which the following is a specification, reference being had to the accompanying drawing, forming a part thereof, in which—

The single figure is a view in perspective of a skate showing my new design.

I claim:

The ornamental design for a roller skate as shown.

NORMAN W. NORMAN.
